United States Patent Office

Des. 229,898

Patented Jan. 15, 1974

229,898

GIRDLE

Marguerite R. Williams, Trumbull, Conn., assignor to
Surgical Appliance Industries, Inc., Cincinnati, Ohio

Filed Dec. 6, 1971, Ser. No. 205,439

Term of patent 14 years

Int. Cl. D2—01

U.S. Cl. D2—2

Fig. 5

Fig. 5

Fig. 4

Fig. 6

Fig. 7

Fig. 8

FIG. 1 is a side perspective view of a girdle showing my new design;

FIG. 2 is a side perspective view of the side opposite thereto;

FIG. 3 is a front elevational view;

FIG. 4 is a rear elevational view;

FIG. 5 is a side elevational view;

FIG. 6 is a side elevational view of the side opposite thereto;

FIG. 7 is a front elevational view with the front panels in an open position; and

FIG. 8 is a front elevational view thereof with the inner panel secured.

I claim:

The ornamental design for a girdle, substantially as shown.
